Des. 67,350

UNITED STATES PATENT OFFICE.

ALBERT O. PRICE, OF COSHOCOTON, OHIO.

DESIGN FOR A RADIOCABINET.

Application filed August 4, 1924. Serial No. 10,374. Term of patent 14 years.

To all whom it may concern:

Be it known that I, ALBERT O. PRICE, a citizen of the United States of America, residing in the city of Coshocton, county of Coshocton and State of Ohio, have invented a new, original, and ornamental Design for Radiocabinets, of which the following is a specification, reference being

had to the accompanying drawing, forming part thereof.

The figure is a perspective view of the radio cabinet showing my new design.

I claim:

The ornamental design for a radiocabinet as shown.

ALBERT O. PRICE,
